MUSICAL DISPENSING CONTAINER

Robert Winthrop Young, Jr., New York, N.Y., and Thomas Jack Armstrong, Jr., Summit, N.J. (both % Colgate-Palmolive Co., Colgate-Palmolive Bldg., 300 Park Ave., New York 22, N.Y.)

Filed June 12, 1963, Ser. No. 287,383
10 Claims. (Cl. 222—39)

This invention relates to dispensing containers and cap structure therefor and particularly to improvements therein wherein discharge of the contents is automatically accompanied by the production of associated sound.

It has been proposed to incorporate music box and like sound producing mechanisms in various types of containers and dispensers but prior to the invention there has been no concept of associating the dispensing of the contents with sound such as music. This is accomplished automatically in the present invention, in the preferred embodiment of which a music box is carried within the cap of an aerosol type container and actuation of the music box is controlled, by operation of the manually moved discharge control member.

A major object of this invention is therefore to provide a novel dispensing container wherein discharge of the contents is automatically accompanied by the production of associated sound.

A further object of the invention is to provide a novel pressurized container assembly wherein operation of a manually movable control member to discharge the contents effects concomitant actuation of a sound or music music producing device.

Another object of the invention is to provide a novel pressurized container assembly wherein operation of a movable control member for discharging the container contents concomitantly actuates a music box built into the assembly.

It is a further object of the invention to provide a novel built-in music box structure in a pressurized container assembly wherein the music box is actuated by the discharge valve control operator. Associated with this object are special arrangements for preventing undesired operation of the music box.

A further object of the invention is to provide a novel pressurized container assembly wherein a container having an outwardly spring biased projecting discharge valve stem enclosed by a cap mounting a control member for the valve stem includes within the cap a sound producing device operatively connected to that member.

Another object of the invention is to provide a novel cap assembly for use with any of a number of conventional type aerosol containers, the cap assembly carrying a music box and an associated valve control plunger.

Further objects of the invention will appear as the description proceeds in connection with the appended claims and the annexed drawings wherein:

FIGURE 1 is a fragmentary elevation partially broken away and in section showing a preferred embodiment of the invention wherein a music box is mounted in the cap of a pressurized container;

FIGURE 2 is a top plan view of the container and cap assembly of FIGURE 1 broken away and sectioned substantially on line 2—2 of FIGURE 1;

FIGURE 3 is a fragmentary elevation in section substantially on line 3—3 of FIGURE 2 showing plunger details; and

2

FIGURE 4 is a fragmentary bottom plan view in section substantially on line 4—4 of FIGURE 1 showing the music box mounting and other detail.

The invention comprises, in its preferred embodiment, 5 a pressurized container 11 of the aerosol type having an upwardly projecting hollow valve stem 12 enclosed by a snap-on cap 13.

The container 11 is of conventional structure and contains liquid or pulverant material incorporated with a discharge propellant gas under pressure, the discharge of the container contents being controlled by a valve diagrammatically shown at 10 which when reciprocable stem 12 is depressed toward the container is opened to permit discharge of the container contents through passage 14 but is otherwise biased toward closed position by the spring acting on the stem. This valve, stem and biasing spring structure all supported within the container on the upper wall of the container is preferably conventional and may be that disclosed in United States Letters Patent No. 2,631,814 to which reference is made for necessary further detail.

As shown in FIGURE 1 the lower open end of cap 13 has a flexible rim structure 15 formed with an internal bead 16 adapted to snap into an annular groove 17 formed in the container wall. This centers and mounts 20 the cap on the container.

The cap is otherwise closed except for a central opening 18 in its top wall 19, and a manual operating plunger 21 projects upwardly through opening 18. At its lower 25 end plunger 21 is formed with a socket 22 rotatably receiving and abutting the upper end of stem 12, and a through passage 23 extends through plunger 21 to terminate in a lateral discharge aperture 24 (FIGURE 1). When plunger 21, which is slidable with respect to cap 13, 30 is depressed the container contents discharge through aligned passages 14 and 23. Plunger 21 is a molded light weight plastic member and in the assembly it is supported substantially wholly by resting on the upper end of valve stem 12, its weight being too small to depress the 35 stem to actuate the valve. The molded arrow 25 indicates the direction of spray discharge.

Cap 13 is formed internally with an integral rib structure 26 on which is mounted a music box assembly 27 comprising a spring motor 28 having an output shaft 29 carrying a drum 31 which is surfaced with rigid pins 32 for coacting with the metal reeds 33 of a comb plate 34. Plate 34 is secured upon rib structure 26, as by screws 35, and is bent up at one side at 36 to provide a bearing support for shaft 29. Motor 28 is mounted on the upper 40 side of the plate.

Spring motor 28 is of a conventional type, being a fixed casing containing a wound spring connected at one end to shaft 29 and at its other end to a ratchet and pawl type release disc which may be held or released by a suitable shiftable control element 37.

Control element 37 extends into the embrace of axially spaced radially projecting abutments 38 integral with plunger 21, so that when plunger 21 is depressed by the operator it moves element 37 to release motor 28 to start 45 turning drum 31 to produce music by the coaction of pins 32 and reeds 33. When plunger 21 is released by the operator it is restored by the spring bias of the valve stem to the FIGURE 1 position where it has moved element 37 back to motor stopping position. Any equivalent linkage may be used between plunger 21 and motor control element 37, the only requirement being that de- 50 55 60 65

pression of the plunger starts rotation of drum 31 and release of the plunger stops drum 31. The axial movement of plunger 21 needed to actuate the container valve is usually very small so that the spacing of abutments 38 can easily be determined.

The spring within motor 28 may be of the very long wound type which is designed to be unwound only after single or repeated actuations of the plunger 21 have exhausted the container contents, or the motor 28 may be provided with a wind stub 38 to be engaged by a removable key 39 inserted through a small opening 41 in wall 19.

A further radial projection 42 integral with plunger 21 is normally located above wall 19 as shown in FIGURE 1, but, when plunger 21 is depressed to operate the valve stem, projection 42 will pass through a recess 43 cut into one edge of opening 18 in only one position of rotation of plunger 21 on its axis. In any other position plunger 21 cannot be depressed because projection 42 will encounter cap wall 19.

Plunger 21 is also formed with a side slot 44 adapted to receive a stationary projection 45 mounted by a flexible neck 46 integral with rib structure 26. As shown in FIGURE 2 slot 44 has sufficient circumferential extent, about 45°, to limit rotation of plunger 21 between two limit positions.

In one such limit position, shown in FIGURE 2, projection 42 is aligned with recess 43 and the indicia ON on wall 19, which means that plunger 21 may be depressed sufficiently to actuate the discharge valve. In this limit position of FIGURE 2, the abutments 38 will be located to actuate motor control member 37, which means that music will be produced during the discharge period.

In the other limit position, which would be reached when plunger 21 is rotated clockwise in FIGURE 2, the projection 42 would align with the indication OFF on wall 19 and would overlie wall 19 closely so that plunger 21 could not be depressed sufficiently to discharge the container contents. It will be noted that in this position the abutments 38 will no longer be aligned with motor control member, so that no music may be produced.

The invention therefore provides an assembly wherein an associated sound producing device and special valve operating discharge plunger are mounted on the cap of a pressurized container, the container contents may be discharged without removing the cap, and discharge of the contents is accompanied by associated sound. The parts are so dimensioned as to accomplish the desired function, and the music device and plunger are pre-assembled with the cap before the cap is placed on the container. The flexible neck 46 enables forcible engagement of projection 45 with slot 44 during assembly and positions plunger 21 during assembly.

The sound produced by the music box may have special association with the particular material being sprayed, or the trade name of that material. For example with silver hair spray, the music box will sound a few distinctive notes of "Silver Threads Among the Gold." Similarly spray of a perfume called Hunting will be accompanied by strains of "A Hunting We Will Go."

It will be noted that the above-described cap assembly containing the music box and special plunger is removably mounted on a standard aerosol container, so that the purchaser need acquire only one complete package and then use the same cap on subsequently purchased containers.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Patents is:

1. For use with a dispensing container containing fluid material under pressure and having a valve operable by a movable control member to selectively discharge said material, a cap adapted to be mounted on said container, means mounting a sound producing unit within said cap, means on said cap adapted to be operatively connected to said control member for actuating said control member to discharge said material, and means within the cap responsive to said actuation of said control member for automatically concomitantly operating said sound producing unit during discharge of said material.

15 2. In the combination defined in claim 1, said means for actuating the valve control member comprising a plunger which has operative connection with said sound producing unit.

20 3. In the combination defined in claim 2, aligned discharged passages formed in said valve control member and plunger and terminating in a laterally directed outlet outside the cap.

4. In combination with a dispensing container containing fluid material under pressure and having a valve operable by an upwardly projecting movable hollow valve stem to selectively discharge said material, said stem being spring biased to valve closed position, means mounting a cap on said container to enclose said stem, means mounting a sound producing unit within said cap, a freely movable plunger seated at one end on said valve stem and projecting through the cover for manual operation, and means within said cover responsive to actuation of said plunger to depress the valve stem for automatically concomitantly operating said sound producing unit during discharge of said material.

30 5. In combination with a dispensing package containing fluid material and a discharge propellant under pressure and having a valve operable by a reciprocable plunger to selectively discharge said material, means mounting a motor driven music box within said package, and means in said package operatively connecting said plunger for automatically operating said music box to provide music accompanying discharge of said material whenever said plunger is depressed to effect discharge of the contents of said container.

45 6. A removable cap assembly for a dispensing package containing fluid material under pressure and having a valve operable by a movable control member to selectively discharge said material, means mounting a sound producing unit within said cap assembly and a manually operable accessible plunger carried by said cap assembly operatively connected to said unit and adapted to be connected to said control member when the cap is on a container.

50 7. In combination, a container for fluent material under pressure having an upstanding hollow valve stem spring biased outwardly to valve closed position, a cap assembly removably mounted on said container to enclose said stem, a motor driven sound producing device mounted within said cap and having a control element shiftable between motor start and stop positions, a movable valve operator carried by said cap assembly in engagement with said valve stem and having a discharge passage that is a substantial continuation of said valve stem and terminates outside the cap assembly, and means

60 65 70 providing an operable connection between said valve operator and said element so that when said valve operator is depressed to effect discharge of the container contents through said passage said motor is started to at the same time produce sound from said device, and when said valve operator is released it is spring returned by the valve stem bias and said motor is stopped.

75 8. In the combination defined in claim 7, said valve operator being a centered plunger which in the assembly rests freely and detachably on the upper end of said valve stem and projects slidably through the cap wall.

9. In the combination defined in claim 7, said valve operator being a centered plunger that is rotatable on the axis of said stem between an active position wherein it may be axially depressed sufficiently to effect discharge of the container contents and an inactive position where such axial depression is blocked.

10. A dispensing package comprising in combination a container of fluid material under pressure provided with a discharge valve having an upstanding valve stem, manual valve operating means connected for actuating said stem to selectively discharge said material, a cap mounted on said container to enclose said stem, said valve operating means projecting through said cap, means mounting a sound producing unit within said cap, and means responsive upon actuation of said valve operating means for automatically operating said sound producing unit dur-

ing discharge of said material comprising an operative connection between said valve operating means and said sound producing unit.
